CLAIM

The ornamental design for a container for dispensing string, as shown and described.

DESCRIPTION

FIG. 1 is an enlarged perspective view of a container for dispensing string showing my new design;

FIG. 2 is a top plan view thereof;

FIG. 3 is a side elevational view thereof, the other side being a mirror image;

FIG. 4 is a bottom plan view thereof;

FIG. 5 is a front elevational view thereof; and,

FIG. 6 is a rear elevational view thereof.

The string shown in FIG. 1 in broken lines is for illustrative purposes only and forms no part of the claimed design.
